NEW JERSEY.

CARBON-PAPER-ROLL-TRIMMING MECHANISM.

Application filed April 27, 1926. Serial No. 104,925.

Our improvement is particularly applicable to carbon paper rolls designed for use in connection with typewriting machines wherein the roll of paper must be supported 5 upon a rigid core. Such rolls are supplied to the trade upon such cores and despite extreme accuracy in cutting and winding the paper, the axially opposite ends of the roll of the paper upon the core are slightly uneven; whereas, it is highly desirable and in fact necessary for the most efficient operation of such typewriting machines, to have such ends of the roll straight and uniform.

Therefore, it is the object and effect of our 15 invention to provide means to render the paper in such rolls of predetermined width, i. e., axial length, and uniformly even at its axially opposite ends, after it is wound.

As hereinafter described, our improved 20 mechanism includes axially opposed mandrels, one of which is arranged to be positively rotated, in connection with such a roll core, but is incapable of axial movement, whereas, the other mandrel may be axially shifted 25 to receive a core between the mandrels and engage the core and thereafter be turned idly, with the core, by the rotation of the other mandrel. Said mechanism includes means to simultaneously trim both the opposite 30 ends of such a roll positioned therein, by means of a pair of circular cutters which are carried by a rock shaft so that they may be manually pressed toward said roll. An important adjunctive feature of the mechanism aforesaid is means to calibrate each roll 35 with reference to the position of said cutters; so that the roll may be properly trimmed with reference to the core which carries it.

40 Our invention includes the various novel features of construction and arrangement hereinafter more definitely specified.

In said drawings; Fig. I is a plan view of a mechanism conveniently embodying our 45 improvement, with a carbon paper roll engaged between the mandrels in position to be trimmed. Fig. II is a front elevation of said mechanism. Fig. III is an elevation of the right hand end of said mechanism, as shown in Figs. I and II. Fig. IV is a transverse sectional view of said mechanism, taken on the line IV, IV in Figs. I and II. Fig. V is a fragmentary sectional view taken on the line V, V in Fig. I, showing the construction and arrangement of the

axially adjustable tail mandrel and its appurtenances. Fig. VI is a perspective view of one of the carbon paper rolls with its core.

In said figures; the mechanism is arranged 60 to be supported upon the frame comprising the head standard 1 and the tail standard 2, rigidly connected by the pair of cylindrical tubular bars 3 and 4, which are rigidly secured in said standards by nuts 6 and 7. 65

The head stock 9 is conveniently a casting having split bearings 10 fitted to said bars 3 and 4 and arranged to be clamped thereon by screws 12. Said head stock 9 has the bearings 15 and 16 for the rotary head mandrel 17 which is prevented from axial movement therein by the collars 18 and 19, and is rigidly connected with the cone clutch member 20, which fits within the conical seat 21 in the belt wheel 22 by which it may be 70 rotated. Said belt wheel is loose and axially movable on said mandrel 17 but has the flange 23 with axially opposite inclined surfaces for alternate engagement with the two radial arms of the rock lever 24 which is 75 fulcrumed in said standard 1 and provided with the spring 25 which normally rocks it to axially shift the clutch belt wheel 22 to the right in Fig. I to release it from said mandrel. However, said rock lever may be 80 tilted to the position shown in Fig. I, in opposition to its spring 25, to thrust said clutch wheel 22 to the left in Fig. I and operatively connect it with said mandrel 17, by means of the lever 26 which is fulcrumed 85 in the bearing 27 on said head stock 9 and provided with the chain 28 extending to a pedal 29, which is depressed by the operator at the beginning of the cutting operation and released at the end of said operation. 90

The tail stock 30 has the bearings 31 fitted to slide on said bars 3 and 4, and has the bearings 32 and 33 for the rotary and axially reciprocating tail mandrel 34. Said mandrel has the collar 36 rigidly secured thereon as an abutment for the spring 37 which bears against the loose collar 38 abutting said bearing 33, and is arranged to continually thrust said tail mandrel toward the head mandrel 17. However, such movement is limited by the milled head 39 which is rigidly connected with said mandrel 34 and by which it may be manually withdrawn to the right in Figs. I and II. The hub 41 of said milled head has the gauge mark 43, 105

- conveniently comprising a circumferentially extending line engraved thereon. The gauge plate 45 has the pointer 46 arranged to co-operate with said gauge mark 43, and said 5 gauge plate is arranged to be adjustably secured in rigid relation with the tail stock 30 by the screws 48 extending from the bearing 33 on said stock through the slot 50 in said plate.
- 10 It is to be understood that the arrangement last above described is such that said tail mandrel 34 may be manually axially withdrawn to the right in Figs. I and II, by its milled head 39, to permit the roll core 15 52 to be inserted between said mandrels, and upon releasing said tail mandrel 34, it is thrust into engagement with said core by its spring 37.
- We prefer to provide the opposed ends of 20 said mandrels 17 and 34 with respective polygonal (conveniently square) core engaging adapters 53 and 54 for engagement with the tubular core 52 which is conveniently formed of molded hard rubber with an 25 axial opening 57 therethrough of the cross sectional configuration of said polygonal adapters; whereby a series of such cores may be successively engaged between said mandrels, in adjustably predetermined axial 30 position.
- Said cores 52 are made of different lengths, in accordance with the width of the web to be wound thereon. However, there is a slight variation in the actual lengths of the cores 35 of each standard size incident to inaccuracies in the manufacture of the cores and to the extent of one thirty-second of an inch, which is the tolerance accepted by the trade. Therefore, we provide means to shift said 40 tail stock 30 toward and away from the head stock 9 to not only permit the same machine to be used for trimming the different standard widths of paper or other web above contemplated; but to compensate for 45 the accidental variations in size of the cores 52; so that the web shall be trimmed flush with the ends of the cores, regardless of the variations in the length of the latter, and as follows: Said tail stock 30, which is free 50 to slide longitudinally upon said frame bars 3 and 4, has the nut 59 detachably rigidly connected therewith by the tap bolt 60, which extends through the washer 61 and the horizontal web of said tail stock 30 into screw 55 threaded engagement with said nut 59 as indicated in Fig. V. Said nut 59 is engaged with the screw shaft 63, which is journaled in the bearing 64 in said standard 2, as indicated in Fig. V, and provided with the 60 collar 66 upon the left hand side of said bearing and the hand wheel 67 upon the other side; whereby said shaft 63 may be turned to shift said tail stock 30 toward and away from the head stock 9.
- 65 The rock shaft 69 extends parallel with the axis of said mandrels and is journaled in the bearings 70 and 71 on said standards 1 and 2, and extends through the bearing 72 on said tail stock 30, and is prevented from axial movement by the collars 73 and 74, 70 which abut against said bearings 70 and 71, and are axially adjustably secured thereon by respective set screws 76. Said rock shaft 69 carries the two cutter heads 78 and 79, 75 having respective keys 81 and 82 engaged in the keyway 83 in said shaft. Said cutter head 78 has the set screw 85 whereby it may be secured in rigid relation with said shaft 69 when set in the proper position, shown in Fig. I, but is axially adjustable on said shaft when said set screw is released. Said cutter head 79 is provided with the sleeve 86 extending through said bearing 72 and provided with the collar 87 at the right hand end of said sleeve; so that said head 79 85 is carried toward and away from said head 78 by rotation of the hand wheel 67 and screw shaft 63 above described.
- Said cutter heads 78 and 79 carry respective face plates 89 and 90 which are rotatably adjustable on said heads to the extent of the arcuate slots 91 in said plates, through which extend set screws 92 by which said plates may be rigidly secured in such adjusted position upon said heads. Said 95 face plates 89 and 90 have respective recessed seats 93 for the cutter bearing bars 94 which may be adjustably rigidly secured therein by the tap bolts 95. Said bars 94 carry respective cutter studs 96 upon which are 100 journaled respective rotary disk cutters 97 which are conveniently formed of thin sheet steel, each with a sharpened circumferential edge.
- Said rock shaft 69 has the lever 99 whereby 105 said cutters may be manually pressed against the roll 100 of carbon paper, or other web, carried by said core 52 between said mandrels 17 and 34; said lever having the spring 101 extending from the rear end 110 thereof to the rod 102 on said head stock 9 and continually tending to turn said rock shaft to uplift said cutters from operative position, when said lever is released.
- As shown in Fig. I; the ends of said bearings bars 94 adjoining said cutters 97 are wedge shaped at 103 to press axially outward the trimmed off portions 104 of said web 100. In order to prevent said cutters 97 from penetrating said core 52, I provide 115 the adjustable stop screw 105 in the bracket 106, which is rigidly connected with said head stock 9. Said screw may be set to limit the approach of said cutters to said core and be secured in such adjusted position by the 120 nut 107.
- It is to be understood that said cutter head 78 is so set upon said rock shaft 69 that the cutter 97 carried thereby is always presented in the proper plane to trim the left 130

hand end of said roll of web 100 as desired. However, said cutter head 79 being adjustable toward and away from said cutter head 78 by rotation of said hand wheel 67 and 5 screw 63 as above described; the pointer 46 is so set upon the tail stock 30 that the gauge mark 43 on the hub of the knob 39 of the mandrel 34 registers with said pointer only when the cutter 97, carried by said cutter head 79, is presented in proper position to trim the right hand end of said web 100. That is to say; the axial position of said mandrel 34 with respect to the mandrel 17 will, of course, vary with the aforesaid 10 accidental variations in the lengths of the cores 52, and the tail stock 30 carrying the right hand cutter 97 is axially adjustable, by rotation of the hand wheel 67, with reference to said mandrel 34 and the gauge mark 15 43 carried by it; to insure the presentation of the right hand cutter in the proper position with reference to said cores in correspondence with the accidental variations in the length of the latter.

20 25 The mechanism above described may be operated as follows: A roll 100 of carbon paper, carried by a core 52, is inserted between said mandrels 17 and 34; the latter being first retracted by its milled head 39 30 and then released to permit both adapters 53 and 54 to enter the opposite ends of the axial opening 57 of said core under pressure of the spring 37 bearing against the collar 36 on said mandrel 34. If said core 35 is of the predetermined standard length; the gauge mark 43 encircling the hub of said head 39 is presented in registry with the index pointer 46. However, if said core is longer or shorter than its nominal size, that 40 fact is manifested by the relative position of said mark and pointer, and, thereupon, the operator turns the hand wheel 67 to bring said pointer 46 into registry with said mark 43. The operator starts positive 45 rotation of the mandrel 17 by depressing the pedal 29. Of course, rotation of said mandrel 17 in engagement with said core 52, causes the latter to idly rotate said mandrel 34. Thereupon, said lever 99 is depressed 50 by the hand of the operator, in opposition to the stress of said spring 101, thus bringing said cutters 97 into contact with the outer convolution of the roll of carbon paper 100. The operator continues to thus press 55 said cutters 97 against the carbon paper 100 with the effect of uniformly trimming the latter at each end at right angles to the common axis of rotation of said mandrels, until said lever 99 comes to rest upon the 60 stop screw 105, which has been so set that said cutters 97 penetrate the innermost convolution of said paper 100, without cutting the core 52. Thereupon, the operator stops 65 the rotation of said mandrels, by releasing the pedal 29; and removes the core 52 with

the trimmed roll 100, by again retracting the mandrel 34 by its head 39. Thereupon, the entire operation above described may be repeated.

As it is necessary to sharpen the cutters 70 97, they are, of course, reduced in diameter by each successive sharpening operation, and though originally of the same diameter, may be thus reduced to different diameters. Therefore, the capacity of said face plates 75 89 and 90 for relative rotary adjustment, is advantageous in that it permits said plates to be so adjusted as to simultaneously present said cutters 97 in contact with the web roll 100, regardless of any differences in 80 diameters of said cutters.

We do not desire to limit ourselves to the precise details of construction and arrangement herein set forth, as it is obvious that various modifications may be made therein 85 without departing from the essential features of our invention, as defined in the appended claims.

We claim:

1. In carbon paper roll trimming mechanism; the combination with a frame comprising parallel bars; of head and tail stocks adjustable toward and away from each other, on said bars; adjustable means arranged to hold said head stock stationary, 90 on said bars; means arranged to adjust said tail stock toward and away from said head stock; a rotary head mandrel journaled on said head stock; means arranged to positively rotate said mandrel; a rotary tail 100 mandrel journaled on said tail stock, in coaxial alinement with said head mandrel, and capable of coaxial reciprocation; a spring encircling said tail mandrel tending to press it axially toward said head mandrel; means 105 limiting such axial movement of said tail mandrel, including a knob head whereby said tail mandrel may be manually retracted, in opposition to said spring; an index member carried by said mandrel and having a 110 circumferential gauge mark; a gauge plate having an index pointer arranged to cooperate with said gauge mark; means arranged to adjustably secure said gauge plate in rigid relation with said frame, including 115 screws extending from said frame through a slot in said plate; core engaging adapters respectively carried by said mandrels at their opposed ends adapted to receive the tubular core of a roll; a rock shaft journaled on said head stock parallel with the axis of said mandrels, and having a key way, extending longitudinally therein; two cutter heads on said rock shaft; face plates on the respective cutter heads, each carrying a cutter stud in eccentric relation with said shaft; means arranged to secure said face plates in circumferentially adjustable relation with said rock shaft and each other, including 120 screws on said heads extending through arcu- 125 130

ate slots in said heads; rotary disk cutters, formed of thin sheet metal, respectively mounted on said cutter studs; a lever on said rock shaft, whereby said cutters may 5 be manually pressed against a roll of carbon paper carried by said core between said mandrels; and an adjustable stop on said frame, in the path of said rock shaft lever, limiting the approach of said cutters to said 10 core; said mechanism being coordinated so that said roll is fixed in predetermined axial position, and said cutters are presented in proper relation with the axial length of the roll on said core, when said gauge mark is 15 brought into registry with said index pointer.

2. In carbon paper roll trimming mechanism; the combination with a frame, carrying relatively coaxially movable head and 20 tail stocks; of screw means arranged to shift, said tail stock toward and away from said head stock; a rotary head mandrel journaled on said head stock; means arranged to positively rotate said mandrel; a rotary tail 25 mandrel journaled on said tail stock, in coaxial alinement with said head mandrel, and capable of coaxial reciprocation; a spring for said tail mandrel tending to press it axially toward said head mandrel; means whereby said tail mandrel may be manually 30 retracted, in opposition to said spring; means limiting axial movement of said tail mandrel, including an index member having a circumferential gauge mark; a gauge plate having a pointer arranged to cooperate with said gauge mark; means arranged to adjustably secure said gauge plate in rigid relation with said frame; core engaging adapters respectively carried by said 35 mandrels at their opposed ends adapted to receive the tubular core of a roll; a rock shaft journaled on said frame parallel with the axis of said mandrels; two cutter heads on said rock shaft, each carrying a cutter stud in eccentric relation with said shaft; means arranged to secure said cutter heads in adjustably predetermined axially spaced relation and with said cutter studs in adjustably predetermined circumferential relation with said rock shaft and each other; 40 rotary disk cutters, respectively mounted on said cutter studs; and a lever on said rock shaft, whereby said cutters may be manually pressed against a roll of carbon paper carried by said core between said mandrels; 45 said mechanism being coordinated so that said roll is fixed in predetermined axial position, and said cutters are presented in proper relation with the axial length of the roll on said core, when said gauge line is 50 brought into registry with said index pointer.

3. In carbon paper roll trimming mechanism; the combination with a frame having head and tail stocks; of a rotary head mandrel journaled on said head stock; means arranged to positively rotate said mandrel; a rotary tail mandrel journaled on said tail stock, in coaxial alinement with said head mandrel, and capable of coaxial reciprocation; a spring for said tail mandrel tending to press it axially toward said head mandrel; means whereby said tail mandrel may be 55 manually retracted, in opposition to said spring; means limiting axial movement of said tail mandrel, including an index member having a circumferential gauge line; a gauge plate having a pointer arranged to cooperate with said gauge line; means arranged to adjustably secure said gauge plate in rigid relation with said frame; core engaging adapters respectively carried by said 60 mandrels at their opposed ends adapted to receive the tubular core of a roll; a rock shaft journaled on said frame parallel with the axis of said mandrels; two cutter heads on said rock shaft, each carrying a cutter stud in eccentric relation with said shaft; means arranged to secure said cutter heads in adjustably predetermined axially spaced relation and with said cutter studs in adjustably predetermined circumferential relation with said rock shaft and each other; 65 rotary disk cutters, respectively mounted on said cutter studs; and a lever on said rock shaft, whereby said cutters may be manually pressed against a roll of carbon paper carried by said core between said mandrels; 70 said mechanism being coordinated so that said roll is fixed in predetermined axial position, and said cutters are presented in proper relation with the axial length of the roll on said core, when said gauge mark is 75 brought into registry with said index pointer.

4. In carbon paper roll trimming mechanism; the combination with a frame; of a rotary head mandrel journaled on said frame; means arranged to positively rotate said mandrel; a rotary tail mandrel journaled on said frame, in coaxial alinement with said head mandrel, and capable of coaxial reciprocation; a spring for said tail mandrel tending to press it axially toward said head mandrel; means limiting such axial movement of said tail mandrel, including an index member having a gauge mark; a gauge plate having a pointer arranged to cooperate with said gauge mark; means arranged to adjustably secure said gauge plate relatively stationary on said frame; means operatively connected with said tail mandrel, whereby said tail mandrel may be manually 85 retracted, in opposition to said spring, to receive the tubular core of a roll between said opposed mandrels; a rock shaft journaled on said frame parallel with the axis of said mandrels; two cutter heads on said 90

- rock shaft, each carrying a cutter in eccentric relation with said shaft; means arranged to secure said cutter heads in adjustably predetermined axially spaced relation and 5 with said cutters in adjustably predetermined circumferential relation with said rock shaft and each other; and means on said rock shaft, whereby said cutters may be manually pressed against a roll of web carried 10 by said core between said mandrels; and an adjustable stop on said frame, in the path of said rock shaft lever, limiting the approach of said cutters to said core; said mechanism being coordinated so that said roll is fixed in predetermined axial position, and said cutters are presented in proper relation with the axial length of the 15 roll on said core, when said gauge mark is brought into registry with said index 20 pointer.
5. In carbon paper roll trimming mechanism; the combination with a frame; of a rotary head mandrel journaled on said frame; means arranged to positively rotate said mandrel; a rotary tail mandrel journaled on said frame, in coaxial alinement with said head mandrel, and capable of coaxial reciprocation; a spring for said tail mandrel tending to press it toward said head mandrel; means limiting such axial movement of said tail mandrel, including an adjusting member; an index member carried by said adjusting member, and having a circumferential gauge mark; a normally stationary index pointer arranged to cooperate with said gauge mark; means operatively connected with said tail mandrel, whereby said tail mandrel may be retracted, in opposition to said spring to receive the 25 tubular core of a roll between said opposed mandrels; a rock shaft journaled on said frame parallel with the axis of said mandrels; two cutter heads on said rock shaft, each carrying a cutter in eccentric relation 30 with said shaft; means arranged to secure said cutter heads in adjustably predetermined axially spaced relation and with said cutters in adjustably predetermined circumferential relation with said rock shaft and 35 each other; whereby said cutters are adapted to cut simultaneously, despite differences in their diameters; and means on said rock shaft, whereby said cutters may be manually pressed against a roll of web carried by said 40 core between said mandrels; said mechanism being coordinated so that said roll is fixed in predetermined axial position, and said cutters are presented in proper relation with the axial length of the roll on said core, when said gauge mark is brought into registry with said index pointer.
6. In roll trimming mechanism; the combination with a frame; of a rotary head mandrel journaled on said frame; means arranged to positively rotate said mandrel; a rotary tail mandrel journaled on said frame, in co-axial alinement with said head mandrel, and capable of coaxial reciprocation; a spring for said tail mandrel tending to press it toward said head mandrel; means limiting such axial movement of said tail mandrel, including an adjusting member; an index member carried by said adjusting member, and having a gauge mark; a gauge plate having a pointer arranged to cooperate with said gauge mark; means operatively connected with said tail mandrel, whereby said tail mandrel may be retracted, in opposition to said spring, to receive the tubular core of a roll between said opposed mandrels; a rock shaft journaled on said frame; two cutter heads on said rock shaft, each carrying a cutter; means arranged to secure said cutter heads in adjustably predetermined axially spaced relation and with said cutters in adjustably predetermined circumferential relation with said rock shaft and 50 each other; whereby said cutters are adapted to cut simultaneously, despite differences in their diameters; and means on said rock shaft, whereby said cutters may be manually pressed against a roll of web carried by said core between said mandrels; said mechanism being coordinated so that said roll is fixed in predetermined axial position, and said cutters are presented in proper relation with the axial length of the roll on said core, when said gauge mark is brought into registry with said index pointer.
7. In roll trimming mechanism; the combination with a frame; of a rotary head mandrel journaled on said frame; means arranged to positively rotate said mandrel; a rotary tail mandrel journaled on said frame, in axial alinement with said head mandrel, and capable of axial reciprocation; a spring for said tail mandrel tending to press it toward said head mandrel; means limiting such axial movement of said tail mandrel, including an adjusting member; an index member carried by said adjusting member, and having a gauge mark; a gauge plate having a pointer arranged to cooperate with said gauge mark; means operatively connected with said tail mandrel, whereby said tail mandrel may be retracted, in opposition to said spring, to receive the tubular core of a roll between said opposed mandrels; a rock shaft journaled on said frame; two cutter heads on said rock shaft, each carrying a cutter; and means on said rock shaft, whereby said cutters may be pressed against a roll of web carried by said core between said mandrels; said mechanism being coordinated so that said roll is fixed in predetermined axial position, and said cutters 60 when said gauge mark is brought into registry with said index pointer, to simultaneously trim opposite ends of such rolls, even with the ends of said cores, without cutting effect upon the latter, despite variations in 65 the length of said cores.

are presented in proper relation with the axial length of the roll on said core, when said gauge mark is brought into registry with said index pointer.

- 5 8. In web roll trimming mechanism; the combination with a frame; of a rotary head mandrel journaled on said frame; means arranged to positively rotate said mandrel; a rotary tail mandrel journaled on said frame, in axial alinement with said head mandrel, and capable of axial reciprocation; means limiting said tail mandrel to coaxial relation with said head mandrel; core engaging means respectively carried by said mandrels at their opposed ends adapted to receive the tubular core of a roll; a rock shaft journaled on said frame; two rotary cutters carried by said rock shaft, and means on said rock shaft, whereby said cutters 10 may be pressed against a roll of web carried by said core between said mandrels; and an adjustable stop on said frame, in the path of said rock shaft lever, limiting the approach of said cutters to said core.
- 15 9. In web roll trimming mechanism; the combination with a frame; of a rotary head mandrel journaled on said frame; means arranged to positively rotate said mandrel; a rotary tail mandrel journaled on said frame, in coaxial alinement with said head mandrel, and capable of coaxial reciprocation; means limiting said tail mandrel to coaxial relation with said head mandrel; core engaging means respectively carried by said mandrels at their opposed ends adapted to receive the tubular core of a roll; a rock shaft journaled on said frame; two rotary cutters carried by said rock shaft; and means on said rock shaft, whereby said cutters 20 may be pressed against a roll of web carried by said core between said mandrels. 25
- 30 10. In web roll trimming mechanism; the combination with a frame; of a rotary head mandrel journaled on said frame; means arranged to positively rotate said mandrel; a rotary tail mandrel journaled on said frame, in coaxial alinement with said head mandrel, and capable of coaxial reciprocation; means limiting said tail mandrel to coaxial relation with said head mandrel; core engaging means respectively carried by said mandrels at their opposed ends adapted to receive the tubular core of a roll; a rock shaft journaled on said frame; two rotary cutters carried by said rock shaft; and means on said rock shaft, whereby said cutters 35 may be pressed against a roll of web carried by said core between said mandrels. 40
- 45 11. In web roll trimming mechanism; the combination with a frame; of a rotary head mandrel journaled on said frame; means arranged to positively rotate said mandrel; a rotary tail mandrel journaled on said frame, in coaxial alinement with said head mandrel, and capable of coaxial reciprocation; means limiting said tail mandrel to coaxial relation with said head mandrel; core engaging means respectively carried by said mandrels at their opposed ends adapted to receive the tubular core of a roll; a rock shaft journaled on said frame; two cutters 50 carried by said rock shaft; and means on said rock shaft, whereby said cutters may be pressed against a roll of web carried by said core between said mandrels; and an adjustable stop on said frame, in the path 55 of said rock shaft lever, limiting the approach of said cutters to said core.
- 60 12. In web roll trimming mechanism; the combination with a frame; of relatively axially movable rotary head and tail stocks carried by said frame; said tail stock being provided with a nut; a screw shaft mounted to rotate in said frame in engagement with said nut; means preventing axial movement of said screw shaft; whereby said tail stock may be axially adjusted toward and away from said head stock by rotation of said screw; a rotary head mandrel journaled on said head stock; a rotary tail mandrel journaled on said tail stock, in axial alinement with said head mandrel; means limiting said tail mandrel to coaxial relation with said head mandrel; means on said mandrels arranged to engage a web roll between them; a rock shaft journaled on said frame; two rotary cutters carried by said rock shaft; means operatively connecting one of said cutters with said tail stock, whereby that cutter may be adjusted toward and away from the other cutter, by rotation of said screw shaft; and means on said rock shaft, whereby said cutters may be pressed against a roll of web carried between said mandrels to simultaneously trim the axially opposite ends of said roll. 65
- 70 13. In web roll trimming mechanism; the combination with a frame; of a rotary head mandrel journaled on said frame; means arranged to positively rotate said mandrel; a rotary tail mandrel journaled on said frame and capable of axial reciprocation; means limiting said tail mandrel to coaxial relation with said head mandrel; roll engaging means respectively carried by said mandrels at their opposed ends; whereby rolls may be successively engaged between said mandrels, in predetermined axial position as to the end thereof engaged with said head mandrel; a rock shaft journaled on said frame; two cutters carried by said rock shaft; means whereby said cutters may be adjustably axially spaced to trim the respectively opposite ends of the roll; means forming a gauge axially movable with said tail mandrel but relatively adjustable with respect thereto; and means, including a rotary screw journaled in said frame and a nut connected with said 75 80 85 90 95 100 105 110 115 120 125 130

- rock shaft, whereby said rock shaft and the cutters thereon may be axially adjusted with reference to said gauge mark; so that said cutters may be manually coordinated with 5 said tail stock in the trimming operation in compensation for variations in such rolls.
14. In web roll trimming mechanism; the combination with a frame; of a rotary head member journaled on said frame; means arranged to positively rotate said mandrel; means maintaining said mandrel in predetermined axial position; a rotary tail mandrel journaled on said frame and capable of axial reciprocation; means limiting said tail 10 mandrel to coaxial relation with said head mandrel; roll engaging means respectively carried by said mandrels at their opposed ends; whereby rolls may be successively engaged between said mandrels, in predetermined axial position as to the end thereof 15 20 25 30 35
- engaged with said head mandrel; a rock shaft journaled on said frame; two cutters carried by said rock shaft; means whereby said cutters may be adjustably axially spaced to trim the respectively opposite ends of the roll; means forming a gauge axially movable with said tail mandrel but relatively adjustable with respect thereto; adjustable means cooperatively connecting said rock shaft with said tail mandrel, whereby said cutters may be manually adjusted to coordinate relation with said tail stock in the trimming operation in compensation for variations in the length of such rolls.

In testimony whereof, we have hereunto signed our names at Burlington, New Jersey, this 19th day of April, 1926.

SAMUEL A. NEIDICH.
GEORGE GARWOOD NEIDICH.
